UNITED STATES PATENT OFFICE.

HAROLD ROWNTREE, OF CHICAGO, ILLINOIS, ASSIGNOR, BY MESNE ASSIGNMENTS, TO NATIONAL PNEUMATIC COMPANY, A CORPORATION OF WEST VIRGINIA.

DOOR-MOVING MECHANISM.

976,924.

Specification of Letters Patent. Patented Nov. 29, 1910.

Application filed April 22, 1909. Serial No. 491,517.

To all whom it may concern:

Be it known that I, HAROLD ROWNTREE, a citizen of the United States, residing at Chicago, in the county of Cook and State of Illinois, have made a certain new and useful Invention in Door-Moving Mechanism, of which the following is a specification.

This invention relates to door moving mechanism, and particularly to power operated means for moving the door and means for controlling the same.

The object of the invention is to provide power mechanism which is simple in construction and efficient in operation for moving doors or the like.

A further object is to provide means of the character referred to which are readily and easily controlled in such a manner that the door will not move unless and until a door moving control device is moved in the direction in which the door is to be moved whereby the movements of the door or the like toward either opened or closed position may be initiated or arrested at will by releasing the control device.

Other objects of the invention will appear more fully hereinafter.

The invention consists substantially in the construction, combination, location and relative arrangement of parts all as will be more fully hereinafter set forth, as shown in the accompanying drawings, and finally pointed out in the appended claims.

Referring to the accompanying drawings, and to the various views and reference signs appearing theron, Figure 1 is a view in side elevation of a door showing the application thereto of a power actuated moving mechanism embodying the principles of my invention. Fig. 2 is a broken view in top plan. Fig. 3 is a broken view in vertical transverse section on the line 3, 3, Fig. 2.

The same part is designated by the same reference sign whereon it occurs throughout the several views.

In the operation of doors and particularly doors employed in street or other cars, subways and elevated railway trains, and the like, which operate past station platforms or landings to take on and discharge passengers, it is a common practice to employ guards on the station platform to attend at the door way to direct or assist passengers in entering or departing from the cars and, as well, to control the operation of the

doors. This operation, however is also frequently accomplished by the conductor on the car. At points in congested travel where large numbers of passengers enter and leave the cars it frequently becomes difficult on account of the jam of passengers inside the door to effect the closing of the door, as the door is liable to crush the passengers, or their arms or other portions of their bodies between the adjacent front edge of the door in its closing movement and the opposed jamb of the door. This difficulty is particularly present in the case of the use of power operated mechanism for moving the door, the door operating motor being once put into operation the door is forced toward its completely closed position under the impelling force of the motive power.

It is among the special purposes of my present invention to provide a construction and arrangement of door mechanism and power device for moving the door and means for controlling the door movements, which means may be under the control of the conductor on the car, or, if desired, under the control of the station platform attendant or guard, whereby the door is moved by power mechanism and yet may be arrested instantaneously at any point in its movement.

In carrying out my invention I employ a door A, which, in the form shown, is of the sliding type being, in this instance, suspended by means of hangers B, carrying supporting rollers C, D, arranged to operate on a fixed track or rail E, in a well understood manner. One or both of the supporting rollers is arranged to be driven by power from any suitable source and by any convenient arrangement of the motor or driving mechanism. In the arrangement shown I connect or secure to the roller D, for instance, a bevel gear wheel G, with which at diametrically opposite points intermesh two bevel gears H, J, oppositely presented and mounted upon a drive shaft K. The drive shaft K, may be driven from any convenient source as, for instance, a motor indicated at L. Intermediate the bevel gears H, J, is a sleeve M, which is mounted upon shaft K, to slide thereon and to rotate therewith while the gears H, J, are loosely sleeved upon the shaft K. At its ends the sleeve M, is provided with friction disks N, arranged to coöperate with the adjacent faces O, of gears H, J, respectively. By shifting the sleeve

M, in one direction or the other, one or the other of the drive gears H, J, will be frictionally locked to rotate with drive shaft K, thereby driving the door supporting roller D, in one direction or the other according to which bevel gear is thus frictionally locked to rotate with drive shaft K. Any suitable or convenient arrangement of control means for shifting the friction sleeve M, may be provided. I have shown a simple arrangement wherein a yoke P, is provided and arranged to engage the sleeve M, said yoke being pivotally supported, as for instance, at R, and an operating extension S, connected to or forming part of the shifting yoke serving to afford means for rocking said yoke as desired. This extension may be continued to any convenient point from which the gearing may be operated or controlled.

From the foregoing description it will be seen that when it is desired to move the door either toward its opened or in its closed position, the attendant or guard on the platform, or the conductor inside of the car, as the case may be, actuates the yoke P, to shift the friction sleeve M, thereby engaging one or the other of the gears H, J, with the driving shaft K, and hence effecting the opening and closing movement of the door. At any point in such opening or closing movement the door may be arrested by simply releasing the yoke or the extension thereof, or otherwise actuating the same, so as to disconnect the gears H, or J, from the drive shaft. This release, of course, may be effected at any point in the movement of the door. Where a large and heavy door is employed having a considerable range of travel, the guard or conductor may manipulate the yoke operating extension or other connection and then walk along with the door as it moves toward its opened or closed position, releasing his pressure on such connection as exigency may require, in order to avoid jamming or injuring passengers who might be in the path of the movement of the door.

If desired the door may be locked in its closed position in any suitable or convenient manner. I have shown a locking latch T, pivotally mounted at a convenient point and arranged to engage a stud or other projection F, on the door when the door reaches its closed position. If desired the operation of the motor may be continuous. In practice, however, it may be desirable to arrest the motor when it is not required for operation, as, for instance, during the run of the car from one station or platform to another. I, therefore, provide motor controlling means by which the motor L, may be arrested or the power shut off therefrom. This control may be effected in any suitable manner, as for instance, by means of a switch arrangement indicated at V, controlled by a hand

lever W, through a rod X. By rocking the lever W, the rod X, is projected in a direction to cause the switch V, to be closed, thereby closing the circuit of the motor L, where an electric motor is employed, or other suitable form of controller where other power medium is employed. If desired the locking latch T, may be released coincidentally with the operation of the motor control devices used, so that when the motor is put into operation, the latch T, will be released. The setting in operation of the motor L, however, does not effect a movement of the door until the friction sleeve M, is properly and suitably operated.

It is obvious that many variations and changes in the details of arrangement and construction would readily occur to persons skilled in the art, yet fall within the spirit and scope of the invention as defined in the claims. I do not desire, therefore, to be limited or restricted to the exact details shown and described.

Having now set forth the object and nature of my invention and a construction embodying the principles thereof, what I claim as new and useful and of my own invention and desire to secure by Letters Patent is—

1. The combination with a door, and means for moving the same, of controlling devices for the door moving means, said devices located upon and adjacent the front edge of the door, and operable in either direction to put in operation the door moving means to move the door in corresponding direction, said devices operating, when released, to arrest the door moving means.

2. The combination with a door, a motor, and connections between the door and motor for moving the door, of means mounted on the door, and located adjacent the front edge thereof, for controlling said connections, and operating, when released, to disconnect said connections and door.

3. The combination with a door, of a motor, gearing actuated by the motor for moving the door, means mounted upon and located adjacent the front edge of the door for controlling such gearing, said controlling means arranged when in normal position to disconnect the door and gearing, but adapted when actuated in one direction or the other from its normal position to connect the door and gearing to move the door in corresponding direction.

4. The combination with a door, and a motor, of gearing intermediate the door and motor and including clutch devices for operatively connecting and disconnecting said gearing, said clutch devices being arranged to normally disconnect the door and gearing but adapted when actuated in one direction or the other to connect the door and gearing to move the door in corresponding direction,

- and means mounted upon and located adjacent the front edge of the door for controlling said clutch devices. 60
5. The combination with a door and a suspending roller therefor of a motor, gearing intermediate the motor and roller, and including friction clutch devices for operatively connecting and disconnecting the roller from such gearing, a control member 10 for said devices located adjacent the front edge of the door operating when moved in either direction from its normal position to connect said gearing to move the roller in corresponding direction and a track on which 15 said roller operates. 65
6. The combination with a sliding door of a power driven supporting roller therefor and means located adjacent the front edge of the door for operatively connecting and disconnecting said roller from its power driven mechanism. 70
7. The combination with a door, hangers therefor, including suspending rollers, a track upon which said rollers operate, gearing for driving one of said rollers, a motor for actuating said gearing and means operated in the direction in which the door is to be moved for connecting said gearing and door, said means operating when released, to 30 disconnect said gearing and door. 75
8. The combination with a door, a suspending hanger therefor, including rollers and a track upon which said rollers operate, of a driving mechanism for one of 35 said rollers, a motor for actuating said driving mechanism and a yoke movable in one direction or the other according to the desired direction of movement of the door for controlling said driving mechanism. 80
- 40 9. The combination with a door, a suspending roller therefor, a track on which said roller operates, a gear connected to said roller, and a drive shaft, oppositely presented bevel gears loosely sleeved upon said shaft and intermeshed with said driving gear, of a motor for driving said shaft and means for connecting and disconnecting said bevel gears and said shaft. 85
10. The combination with a door, of a suspending roller therefor, a track upon which 45 said roller operates, a gear connected with said roller, a driving shaft, oppositely presented, beveled gears loosely sleeved upon said shaft and intermeshed with said gear, a friction sleeve mounted on said shaft for sliding movement thereon and connected to 50 rotate therewith and interposed between 90
- said beveled gears, means for shifting the said friction sleeve back and forth upon said shaft, and means for driving said shaft. 95
11. The combination with a door and a suspending roller therefor, of a motor, connections between the door suspending roller and motor, means operating in the desired direction of movement of the door for controlling said connections to move the door, and a locking device for locking the door in closed position. 100
12. The combination with a door and a suspending roller therefor, of a motor connections operated by the motor and connected to the roller for moving the door, means for controlling said connections to move or arrest the door, and means for controlling the motor. 105
13. The combination with a door, power mechanism for moving the same, a controller therefor, said controller being mounted upon the door adjacent its front edge, and means operated by the controller for rendering the power mechanism effective to move the door in one direction or the other according to the direction in which the controller is actuated, such operating means remaining effective only so long as the controller remains in its applying position. 110
14. The combination with a door, of an operating motor therefor, and means mounted upon and arranged adjacent the front edge of the door, and operated by pressure thereon, in either direction from its normal position for operatively connecting the motor and door, said means arranged when in its normal position to disconnect the motor and door. 115
15. The combination with a door, a suspending roller therefor of power devices for driving said roller, and means adjacent the front edge of the door for controlling said power devices. 120
16. The combination with a door and a suspending roller therefor, of a motor for driving said roller, locking means for the door when in closed position, and means for unlocking the door and starting the motor in unison. 125
- In testimony whereof I have hereunto set my hand in the presence of the subscribing witnesses, on this 19th day of April A. D., 1909.
